(57) **CLAIM**

The ornamental design for a mirror bezel, as shown and described.

DESCRIPTION

This patent application is related to U.S. patent application Ser. Nos. 18/298,099 and 29/873,868, both filed Apr. 10, 2023.

FIG. 1 is a front perspective view of a mirror bezel;

FIG. 2 is a rear perspective view thereof;

FIG. 3 is a top view thereof;

FIG. 4 is a bottom view thereof;

FIG. 5 is a first side view thereof;

FIG. 6 is a second side view thereof;

FIG. 7 is a third side view thereof; and,

FIG. 8 is a fourth side view thereof.

The dashed broken lines in the figures illustrate portions of the mirror bezel that form no part of the claimed design.
